TOY AIRPLANE

John R. Harris, New York, N. Y.

Application February 2, 1945, Serial No. 575,919

8 Claims. (Cl. 46—17)

1

This invention concerns toy aeroplanes and refers, more particularly, to a toy capable of flight on being swung in a circle at the end of a string, and having a propeller which under such conditions revolves and simulates on a small scale but with great realism the sound of a real aeroplane engine as heard from the ground.

An aeroplane having this and other features was first described by me in U. S. Letters Patent No. 1,776,222. Subject application relates to improvements in the earlier toy. Chief among the other features just mentioned was that the toy could be assembled from suitably slotted and scored cardboard blanks without the use of tools or adhesives and with very few pins or other fastenings.

An object of the present invention is to make the sound emitted by the propeller a more faithful imitation of the sound of a real engine.

Another object is to decrease the number of blanks necessary for assembling the plane.

Another object is to simplify the contour of the remaining blanks.

Another object is to provide overlapping and interlocking tabs, each of which extends integrally with the plane body for the entire distance of its opposite end corresponding tab, producing a more rigid interlocking construction.

Another object is to reduce the number of locations at which the blanks must be interlocked to produce the assembled plane.

Another object is the provision of a connection for the string which will permit more intricate maneuvering of the toy, such as landing it, taxiing, and flying above the head.

Other objects will become apparent in the following specification.

In accomplishing the objects of the present invention, it was found desirable to provide a metallic propeller having rearward facing cam surfaces engaging forward facing metallic cam surfaces attached to the body of the plane, resulting in axial reciprocation of the propeller during revolution, the attendant noise being conducted immediately to the entire plane body which acts as a sounding board, eliminating the separate sounding board of the earlier model. The propeller is rendered more noisy by being mounted slightly eccentrically. A further improvement in the propeller is that the leading edges are rounded, minimizing the possibility of the user being cut by sharp edges. This rounding preferably occurs by forming a tube from which the blades trail, the tube constituting a reinforcement of the propeller along its entire length. The propeller shaft is more firmly affixed by

2

being hooked into a specially provided slot. The simulated engine noise is amplified by mounting the propeller on the apex of a substantially pyramidal nacelle communicating with the plane body, whereby a megaphone effect is obtained. The form of the invention comprising a downwardly open body moreover requires no rearward intra-engagement in order to obtain necessary rigidity. The forward intra-engagement of the body provides the aforementioned substantially pyramidal nacelle and also provides integrally an axle housing, eliminating the separate landing frame of the former model. In an alternative form, the landing frame has been provided with an interengagement with the body to fix it against lateral movement. Additional motor gondolas, each carrying a propeller, have been devised for attachment to the wing, making the plane more noisy and more visually impressive.

The rudder has been stabilized in the vertical plane by two pairs of vertically displaced engagement with other members.

Holes have been located on the wing on either side of the body and near the center of gravity of the completely formed plane for the attachment of the string which extends downward through one hole and upward through the other hole and having each end separately knotted to prevent its pulling through, thus permitting the toy to be flown in one direction or in the opposite direction by drawing the free length of cord so that it extends through one hole or the hole on the opposite side of the wing.

In operation, the above improvements result in a simpler and more rigid toy and one which gives off a louder and more realistic simulation of engine noise and is capable of more extensive maneuvers.

The invention will appear more clearly from the following detailed description when taken in connection with the accompanying drawings showing, by way of example, preferred embodiments of the inventive idea.

In the drawings:

Figure 1 is a vertical median longitudinal section of the toy embodying the present invention;

Figure 2 is a section along the line 2—2 of Figure 1;

Figure 3 is a section along the line 3—3 of Figure 1;

Figure 4 is a section along the line 4—4 of Figure 1;

Figure 5 is a plan view of the toy;

Figure 6 is a detail of the propeller mounting;

Figure 7 is a side elevation of the toy;

Figure 8 is a plan view of the cardboard blanks

3

and other parts of the plane in flat condition, as sold.

The parts of the aeroplane, as illustrated in Figure 8, comprise the body blank 10, wing 11, extra gondola blanks 12, rudder 13, elevator 14, propeller 15, stylus 16, resonator 17, axle 18, and wheels 19. The body blank 10 has a median longitudinal scored line 20 along what may be called the backbone of the plane, this being the high portion of the plane as assembled, the material to either side of it being bent down therefrom to form the sides 21, 22. The broken lines in Figure 8 only denote score lines on the blanks rather than hidden lines as usual, the score lines being indented lines created to facilitate folding of the flat pieces into pieces constituting parts of the toy plane.

Body blank 10 further has two integral nacelle tabs 23, 24 located forwardly and adapted to form the nacelle 25 upon being folded. The tab 23 comprises everything outward of the score line 26 on which the slit 27 is located. This includes the triangular portion 28 which has a projection 29 beyond the short boundaries 30 and 30A which are substantially perpendicular to the side boundary line 31 of the body blank 10. The score line 32 separates triangle 28 from the polygon 33 comprising the boundary 34 extending at an acute angle to the score line 32, the boundary 35 also at an acute angle to score line 32 and at an oblique angle to boundary 34, and the boundary 36 extending at an oblique angle to the front line 37 of body blank 10, the boundary 38 extending substantially parallel to front line 37, and the boundary 39 connecting lines 37 and 38. A catch tab 40 is formed at the juncture of boundaries 34 and 35.

The tab 24 comprises all the material outward of the score line 41, including the triangle 42, which has a projection 43 beyond the short boundary 44 which is substantially perpendicular to the side boundary line 45 of body blank 10. Tab 24 also includes the rectangular strip 46 rearwardly adjacent triangle 42 across score line 47 and the triangle 48 across score line 49. Triangle 48 is bounded outwardly by score lines 50, 51 separating it from terminal tabs 52, 53, which are separated from each other by slit 54. Lock tab 55 projects from the outward boundary 56 of triangle 42.

The areas included by the triangle 48, and the terminal tabs 52 and 53 separated by slit 54 combine to form a jam tab, which in folded position permits the slit 54 to engage the catch tab 40 of the polygon 33, while the outer boundaries of tabs 52 and 53 bear against the folds on score lines 26 and 41 respectively and the surface of the triangular area 48 bears against the outer boundary 34 of polygon 33 (see Figures 1 and 2). The frictional contact of the aforementioned elements causes the jamming effect to hold these parts in position.

The propeller shaft mounting is provided by three score lines 57, 58, 59. The central line 57 is a prolongation of backbone line 20 and perpendicularly bisects the front boundary 37. The side lines 58, 59 are the sides of an isosceles triangle based on line 31, the apex of which is on the backbone line 20, the apex being cut out to form the rearward pointing arrowhead 60 and shaft 61, the shaft 61, which is a slot, being symmetrically disposed on the central line 57. Outside the lines 58, 59 are the nacelle side portions 62, 63, merging into the body side portions 21, 22, respectively.

To the rear of the nacelle sides 62, 63 extend

4

the curved wing slits 64, 65, substantially longitudinally of body 10. The rearmost portion of the body 10 has the form of a rather blunt trefoil, of which, after folding, the outside leaves 66, 67 represent from either side the silhouette of the rear wheel of the plane and the central foil 68 represents the tail. The rearmost portion of body 10 also bears the elevator slits 69, 70 and the forward and rear rudder slits 71, 72, respectively.

10 The wing 11 comprises body engaging tabs 73, 74, and tabs 75 and slots 76 for engaging the additional gondolas 12. It also has two small holes, 77, 77A, to either side of and relatively close to the central point laterally of the plane and near the center of gravity of the assembled toy.

The gondola blanks 12 comprise the central longitudinal belly score line 78, the nacelle side score lines 79, 80, the center nacelle score line 81 in prolongation of line 73, and the rearward fac-
20 ing cut out arrow-head 82 and shank 83, which is a slot, all symmetrically disposed at the apex of lines 79, 80 and on line 81. Outside the lines 79, 80 are the gondola nacelle side portions 84, 85. Score lines 86, 87 extend rearward substantially perpendicularly to front boundary 88 and outward of the last mentioned score lines are the substantially triangular nacelle top tabs 89, 90, with forwardly directed apexes and of which the score lines 86, 87 form the hypotenuses. Tab 91 ex-
25 tends from the long side of tab 89 and slot 92 is located on score line 87 longitudinally coincident with tab 91. Jam tab 93 extends rearwardly from tab 89 and score line 84. The nacelle tail portion comprises the two substantially kidney-shaped tail tabs 95, 96 partially articulated by the inwardly and rearwardly extending slits 97, 98.

The rudder 13 comprises the downward and forward extending tail tab 99 and the three winged tab 100, the latter comprising lobe 101 extending downward with its rear surface 102 substantially at right angles to the lower boundary 103 of the rudder 13. The lobe 101 terminates forwardly in a line 104 substantially parallel to the boundary 103, the lower tab 105 ex-
40 tends downward therefrom substantially perpendicularly and terminates forwardly in a small catch tab 106, whence the forward tab 107 ex-
45 tends substantially horizontally forward, and then back to the rudder 13, a slit 108 being formed between the two. Forward tab 107 thus engages the two body sides 21, 22 as they meet at the backbone line 20.

The elevator 14 has a forward slit 109, a rear slit 110, and a tab 110A.

As best seen in Figures 1 and 6, the propeller 15 is fabricated preferably of light sheet steel by first embossing a longitudinal rib, extending from tip to tip of the propeller blades; the open edges of said rib are then closed to form a substantially cylindrical tube 111, slightly constricted at each end and suspended slightly eccentrically by the stylus 16 passing through it. The blades 112, 113, extend rearwardly from this tube 111 with which they are integral, one of them, for instance 112, further extending to the right thereof, while the other, 113, extends to the left thereof. A longitudinally central tab 114 extends part way around the tube 111, being integral with it and adapted to present an uninterrupted curved cam surface thereon.

The stylus 16 acts as a fixed shaft on which the propeller 15 loosely revolves. It may be an ordinary small nail, the body of which includes a square terminal hook 116 and a slight angle 117

substantially midway between the hook 116 and the head 118.

The resonator 17 may be a well known metallic paper fastener, comprising an oblong body, a central hole 119 which is usually diamond shaped, and somewhat inward of its opposite ends, a sharp pin-like or claw-like projection 120 and a hole 121. The hole 121 can advantageously be replaced by a second projection 120.

The plane is assembled by placing the propeller 15 and resonator 17, bent as in Figure 6, along the line 122 of Figure 8, on the stylus 16 with the hole 115 to the rear and the hole 119 to the front, hooking hook 116 in slot 61, bending the sides 21, 22 of body 10 downward from backbone line 20, simultaneously depressing central score line 51, whereby the triangle included in the score lines 58, 59 sinks into the nacelle, frictionally engaging stylus 16 along substantially its entire length and positively through hook 116 preventing it from pulling out. All the score lines within or bounding tabs 23 and 24 are then bent down, tab 24 is brought over tab 23 and lock tab 55 inserted in slit 27, the polygon 33 then acting as a reinforcement by extending interiorly to the ridge of the body 10 and nacelle 25, or from bottom to top thereof.

The body sides 21, 22 are thus locked up to form the nacelle 25 by opposite and corresponding tabs 23, 24, each of which extends integrally with the body for the entire length of its opposite and corresponding tab. The resonator 17 is now pressed into place on the nacelle sides 62, 63, as shown in Figure 6, the line 122 now constituting its front line except that hole 119 forms a recess in that line.

The boundaries 30, 30A and 44 are now longitudinally coincident, as well as the projections 29, 43. The axle 18 and wheels 19 are now placed over projections 29, 43 and the triangle 48, and terminal tabs 52, 53 stuffed up into the nacelle, the triangle 48 resting on the boundary 34 and the tabs 52, 53 passing to either side of polygon 33 and extending downward and outward therefrom, while the catch tab 40 engages the slit 54. The axle 18 is thus encased in a housing (see Figure 1) formed by the boundaries 30, 30A, and 44 forwardly, by projections 29 and 43 below, by strip 46 rearwardly and by a portion of triangle 48 at the top.

The tabs 73, 74, of wing 11 are now bent down and the wing slipped into the curved wing slits 64, 65, the tabs 73, 74 then being straightened out in order to lock the wing in place by engaging the interior surfaces of the body side portions, 21, 22. The wing 11 is thus maintained in cambered shape by the curved wing slits 64, 65, as best seen in Figure 1.

A propeller, stylus and resonator, assembled as above, are next folded into each gondola 12 by placing the stylus 16 below line 81 and the hook 116 up through slot 83, bending line 81 upward simultaneously with bending the belly line 78 and lines 79 and 80 downward, folding tab 89 over tab 90 and doubly locking them together by means of tab 91 inserted in slot 82 and jam tab 83 folded back along line 94 to enclose tab 90 and simultaneously jam against the interior surfaces of the locked-up gondola nacelle sides 84, 85. The slits 97, 98 are then interengaged with one of the slots 76 and the corresponding tab 75 slipped into the gondola nacelle under tabs 89, 90, 93 to lock the gondola on the wing.

The elevator 14 is slipped through the eleva-

tor slits 69, 70 and forwardly positioned against lateral movement by the tab 110A.

The forward tab 107 of rudder 13 is inserted in slit 71 point foremost and advanced forward and downward as far as possible before bringing the rudder to its normal position. A slight up and down rocking motion of rudder 13 around the inner end of slit 108 as a pivot will then serve simultaneously to introduce lower tab 105 into slit 109, lobe 101 into slit 71 and tail tab 99 into slits 72 and 110. Rudder 13 is thus locked against forward motion by the interengagement of slits 71 and 108 and against rearward motion by lobe 101 engaging slit 71 substantially perpendicularly at 102 and lower tab 105 similarly engaging slit 109. Rudder 13 is further maintained vertical by both the three winged tab 100 and tail tab 99 engaging both the body 10 and elevator 14. The slits 109, 110 are thus some distance below the slits 71, 72 and the geometrical plane which contains them is substantially vertical. Furthermore, forward tab 107 snugly engages the backbone line 20 of the plane interiorly.

A long cord is now passed down through one of the holes 71, 77A, and up through the other, each end then being knotted separately. The result is that the cord extends between the holes 71, 77A beneath the wing 11, and either end of it may be drawn out to form a free end extending above the wing 11 from either hole 71 or 77A. If the free end extends from hole 77A on the right wing of the plane, the plane may be swung in a circle which passes from left to right in front of the swinger, while by drawing out the cord 35 through hole 77 on the left wing the plane is adapted to be swung in a circle passing from right to left in front of the person swinging it. The above is possible either with or without attaching the extra gondolas 12, but when they 40 are attached, the plane, being heavier, can be swung in a larger circle.

The relative motion between the swung plane and the air through which it travels causes the propellers 15 to revolve on the styluses 16. It has been noted that the blades 112, 113 extend rearward from the tube 111, and also laterally therefrom, one blade to the right, the other to the left, both of which bear the same clockwise relation to the tube 111, therefore air impinging on these blades from the front will cause a revolution of propeller 15 toward the clear sides of tube 111 opposite the blades 112, 113, in other words the propeller as viewed in Figures 6 and 8 would travel counter-clockwise. This is an important safety feature, as the leading edge of each blade is the tube 111, which cannot cause accidental cuts because it is rounded. A further advantage of the construction is that a tube is a very strong shape, and will resist deformation in case of collision.

The propeller 15 in revolving on stylus 16 bears rearwardly against resonator 17, which has been designed to present a cammed surface rather than a smooth bearing surface, by reason of the hole 119 which due to the bending of resonator 17 on line 122 presents from the side the appearance of a recess in the front surface of the resonator 17, into which the propeller 15 may settle momentarily when in proper angular relation, and out of which it must climb in order to continue revolving. The tubular backbone 111 of the propeller 15 is the surface which rides into and out of the notched front end of the resonator 17. The result is a considerable reciprocation of propeller 15 axially of stylus 16,

taking place twice per revolution. This movement of rear surface of the propeller 15 in contact with the depression formed by the hole 119 in the resonator 17 when bent on line 122 gives rise to considerable noise, which is transmitted by the stylus and resonator to the nacelle 25 and body 10, the nacelle further acting as a megaphone to cast the sound into the downwardly open plane interior which considered alone or together with the nacelle, is a perfect sounding board. Since the hole 115 by which propeller 15 is suspended on stylus 16 is not quite central, propeller 15 is rendered still more noisy in revolution. The noise given off by the plane in flight is similar to the sound of a real miniature aeroplane engine. At greater speeds, as when swinging the plane with ten to fifteen feet of string, a hum develops similar to the propeller noise of a real plane.

It is apparent that the illustration shown above has been given by way of illustration and not by way of limitation and that the above structure is subject to wide variations and modifications, without departing from the scope or intent of the present invention. All of such variations and modifications are to be included within the scope of the present invention.

What is claimed is:

1. A toy aeroplane comprising, in combination with a nacelle portion and a propeller, a stylus constituting a fixed shaft for said propeller, said stylus comprising a head, a propeller supporting portion co-axial with said head, an angular portion bent from said propeller supporting portion, a substantially square hook at the end of said angular portion, the said nacelle portion having a depression the bottom of which acts as a supporting wall for the angular stylus portion and an anchorage for the hook.

2. A toy aeroplane comprising, in combination with a nacelle portion and a propeller, a stylus constituting a fixed shaft for said propeller, said stylus comprising a terminal hook portion, said nacelle portion comprising an opening formed therein, said opening having the shape of an arrow head and shaft and being symmetrically disposed on a central score line and adapted to receive said hook portion, said nacelle portion further comprising integral portions enclosing and frictionally engaging said stylus substantially along the entire length of said stylus.

3. A toy aeroplane comprising a body portion of substantially triangular cross section, said body portion comprising an interlocking nacelle portion, said nacelle portion comprising integrally a polygonal portion extending from bottom to top thereof interiorly and constituting a reinforcement disposed substantially centrally and longitudinally of said body portion.

4. A toy aeroplane comprising a body portion, said body portion comprising a median longitudinal line separating said body into two side portions and constituting a backbone line defined by said side portions, said portions extending downward therefrom, said body portion further comprising forward and rear rudder slits formed therein and located on said backbone line, said aeroplane further comprising an elevator located below said rudder slits and having forward and rear slits formed therein, said aeroplane further comprising a rudder, said rudder comprising a rear tab engaging said two rear slits and a three winged tab, said three winged tab having

two portions engaging said two forward slits and also having a portion engaging said side portions at said backbone line.

5. A body blank for a toy aeroplane comprising an elongated piece of sheet material, said blank comprising a body portion having formed therein a median longitudinal score line constituting a backbone line, said body portion further having a front boundary extending perpendicularly to said backbone line, said body portion further having formed therein score lines constituting substantially the sides of an isosceles triangle based on said front boundary and having its apex on said backbone line, said body portion further having formed therein at said apex an opening in the shape of a rearward pointing arrow head and shaft symmetrically disposed on said backbone line, said blank further comprising two integral nacelle tabs, said tabs comprising triangular portions adjacent said body portion, said body portion further comprising adjacent said tabs short boundary portions extending substantially perpendicular to the side boundaries of said body portion, said triangular portions comprising portions projecting beyond said short boundary portions, one of said nacelle tabs comprising a slit formed therein along part of its inner boundary and further comprising a polygonal outer portion, the other said nacelle tab comprising a lock tab on its outer boundary, a rectangular strip rearwardly adjacent said triangular portion, a further triangular portion to the rear of said rectangular strip and terminal tab portions outward of said second mentioned triangular portion, said body portion further having formed therein slits adapted to receive a wing portion, slits adapted to receive an elevator portion, and slits located on said backbone line and adapted to receive a rudder portion, said body portion further having a rear portion in the shape of a blunt trefoil.

6. A toy aeroplane comprising a body folded along a median longitudinal line to produce a substantially triangular cross sectional aspect, said body comprising corresponding and interlocking tabs, each of said tabs being integral with said body and extending therealong for the entire length of the tab, one of said interlocking tabs including a pair of angularly disposed edges and a catch tab formed at the juncture of said edges, the other of said tabs comprising a triangular portion hinged at its base and a pair of terminal tabs hinged one at each of the other sides of the triangular portion, the said terminal tabs being separated by a slot formed therebetween, the said triangular portion, terminal tabs and slot in combination with the aforementioned angularly disposed edges and catch tab forming jamming means between the said interlocking tabs.

7. In a toy aeroplane having a body portion and wing portions; a stationary propeller shaft disposed on one of the portions and protruding therefrom, a propeller for the shaft, the propeller having a hub and blades, the hub being rotatable and slidably on the shaft, a bent plate disposed in the portions and coacting with the propeller, the plate comprising a pair of angularly disposed surfaces, the juncture of the surfaces having a recess coacting with the hub of the propeller.

8. A toy aeroplane, comprising, in combination, a wing portion, said wing portion having openings formed therein on opposite sides of the longitudinal center line of the aeroplane and to

the side of the center of gravity of the aeroplane, and a cord extending slidably downwardly through one of said openings and upwardly and out of the other opening, one end of the cord being knotted and engaging the walls of one of said openings.

JOHN R. HARRIS.
